(57) **CLAIM**

The ornamental design for a watch case, as shown and described.

DESCRIPTION

FIG. 1 is a perspective view including a front, top and one side of the watch case;

FIG. 2 is a perspective view of the rear, a top, and an opposite side of the watch case of FIG. 1;

FIG. 3 is a perspective view of a bottom and one side of the watch case of FIG. 1;

FIG. 4 is a planar view of the top of the watch case of FIG. 1;

FIG. 5 is a planar view of the rear of the watch case of FIG. 1;

FIG. 6 is a planar view of the opposite side of the watch case of FIG. 1;

FIG. 7 is a planar view of the front of the watch case of FIG. 1;

FIG. 8 is a planar view of one side of the watch case of FIG. 1; and,

FIG. 9 is a planar view of the bottom of the watch case of FIG. 1.

The broken lines show a strap for displaying the environment in which the design is associated and form no part of the claimed design.

1 Claim, 9 Drawing Sheets
